(57) **CLAIM**

The ornamental design for a custom design for rotating member, as shown and described.

DESCRIPTION

FIG. 1 is a front elevational view of a custom design for rotating member of the present invention showing my new design; and,

FIG. 2 is a perspective view of the custom design for rotating member of FIG. 1.

The broken lines shown in the Figures are intended to show environment, but form no part of the claimed design.
